FREDERICK P. HITCHCOCK, OF KANSAS CITY, MISSOURI.

VAPOR-VACUUM CONTROLLER.

1,202,999.

Specification of Letters Patent. Patented Oct. 31, 1916.

Application filed March 29, 1916. Serial No. 87,578.

To all whom it may concern:

Be it known that I, FREDERICK P. HITCHCOCK, a citizen of the United States, residing at Kansas City, in the county of Jackson and State of Missouri, have invented a new and useful Vapor-Vacuum Controller, of which the following is a specification.

My invention relates to vapor-vacuum controllers of the class which are used in steam heating systems to facilitate the expulsion of the air in the pipes of the system.

The objects of my invention are:—first, to provide a cheap, durable and efficient automatic vapor-vacuum controller which may be connected with the common return pipes of the steam heating system to expel the air from the system and exclude the atmosphere therefrom; second, to provide a valve for the outlet which is operable by the thermostatic action of the controller; third, to provide a brass tube within the controller which shall expand by the heat of the steam vapor circulating in the system; fourth, to provide a seat for the inner end of the brass tube and a bore therein adapted to receive a rod having outwardly of the controller adjustable means responsive to the expansive movements of the brass tube; fifth, to provide a pivotally mounted lever having a valve at its free end adapted to close the outlet and provided with fulcrums or knife bearings; sixth, to provide a sleeve for the outer end of the rod and having an outwardly extending annular flange on its inner end and a cup-shaped washer engaged by said flange and adapted to contact the fulcrum bearings on the valve lever and a spring under tension on the sleeve and pressing on said cup-shaped washer; and seventh, to provide a bracket which will serve to shield and protect the valve from dust particles and provide convenient means for fastening and suspending the controller from the ceiling or other suitable support. I attain these and other objects by means of the mechanism illustrated in the accompanying drawing, in which—

Figure 1 is a vertical section of the controller, in part, and showing the thermostatic principle, the valve and the valve controlling mechanism in operative position; Fig. 2 is a view of the head of the controller

on the line IV—IV in Fig. 1; Fig. 3 is a view of the inner side of the head, taken on the line V—V in Fig. 1; Fig. 4 is an elevation of the inner brass tube, in fragments, and showing the baffle or deflecting plates attached to its sides; Fig. 5 is a plan view from the inner side of the washer at the inner end of the brass tube, and Fig. 6 is an end view of the cup-shaped washer on the inner end of the sleeve.

Similar numerals of reference refer to corresponding parts through the several views.

Referring to the drawings—The cylindrical outer iron shell 1, is provided with a closed end 2 and an inlet 3, the latter having a nipple 4, secured therein and connected with the common return pipe 5, in a steam heating system, not shown. An outlet passage 6, is formed in the shell and communicates with an opening in the head, hereafter described, having an annular valve seat 7, which is formed at the outer end of the outlet on a head 8. The head 8, is adapted to close the opposite end of the shell, with the exception of the outlet opening 6, and a circular opening 9, centrally therethrough and which communicates with the interior of a brass tube 10, which is secured by its outer end to the inner side of the head by solder or any other suitable means. The brass tube is projected into the shell to adjacent the inlet 3. A seat 11, is formed on the inner side of the head at the edge of the opening 9, therein, in which seat the brass tube 10, is rigidly secured. A channel 12, is formed on the inner side of the head 8, outwardly adjacent the brass tube, in which channel the shell 1, is rigidly secured by any suitable means as solder and the like. The shell 1, is expanded outwardly in curved line adjacent the outlet 6, as shown at 13, in Fig. 1, for the purpose of providing a suitable orifice for the prompt expulsion of the air from the pipes in the heating system. A circular plug 14, having an annular seat 15, adapted to receive the inner end of the brass tube 10, is provided centrally with an inwardly extending boss 16, having a bore 17, adapted to receive the screw end of a rod 18, which is extended outwardly of the controller a suitable distance. Vertically extending posts 19, are mounted on the head 8, and are

adapted to receive a rock shaft 20, which pierces the bowed arms 21, of a lever 22, the latter being provided at its free end with a valve 23, having a stem 24, piercing the adjacent portion of the lever and provided at its upper end with an adjusting nut 25, adapted to hold the valve in place. At the inner end of the bowed arms 21, of the lever 22, a transversely extending fulcrum or knife bearings 26, are formed to substantially register with the rod 18. The fulcrums or knife bearings 26, are designed and located to provide a fulcrum for the lever 22, and to receive the pressure of the mechanism herein-
after described. A guide 27, extending in the form of a semi-circle about the rod 18, is formed integral with the lever 22, but is spaced from the rod a distance adapted to allow the functional vibrations of the lever 22 without contacting the rod. A sleeve 28, is provided on its inner end with an outwardly extending annular flange 29, and is slidably mounted on the outer end of the rod 18. Screw threads are provided on the outer side of the sleeve and are adapted to receive adjusting nuts 30, and a cup-shaped washer 31, is movably mounted on the inner end of the sleeve. The washer 31, is provided with an inwardly extending annular flange adapted to engage the flange on the sleeve.
A coiled spring 32, is mounted on the sleeve 28, the inner end thereof is made to press on the washer 31, and its outer end to press on the inner side of the inner nut 30.
The tension of the spring forces the edge of the cup-shaped washer 31, to press on the fulcrums or knife bearings 26, thereby forcing the lever 22, and the valve carried by the lever to its seat, when the rod 18, is moved inwardly by the expansion of the brass tube 10. An adjusting nut 33, is movably mounted on the outer end of the rod 18, and is adapted to force the sleeve forwardly to regulate the pressure which opens the valve independently of the adjustment of the spring tension. An upwardly extending outwardly projecting bracket 34, is formed on the outer side of the shell 1, and over-spreads the valve. The projecting portion of the bracket provides a shield or cover for the valve to prevent dust particles and other substances interfering with the valve or valve seat. A bracket 35, is formed on the shell at the opposite end thereof and conforms substantially with the bracket 34, except that the projecting portion is directed inwardly. The brackets are perforated and the perforations adapted to receive fastening devices to fasten or suspend the controller from the ceiling or other support. Plates 36 are attached on opposite sides of the tube 10, and are adapted to contact the inner side of the shell 1, for the purpose of holding the tube substantially in line.

In steam heating systems the steam vapor

rises from the boiler through the circulating pipes and returns to the boiler by a return pipe which is used in common by the steam, water and air. The air is expelled at the individual radiators connected in the system or at a single point in the common return adjacent the boiler, which point is subjected to the control of apparatus adapted to operate by the pressure in the system to permit the expulsion of the air in the pipes.

The vapor-vacuum controller constructed as herein-above described operates substantially as follows: When the steam pressure rises the air is forced to move in advance of the steam vapor and opens the valve 23, and is rapidly expelled from the entire system. When the steam vapor enters the controller, the brass tube becomes heated thereby and expands rapidly. The force exerted by the expansion of the brass tube in longitudinal direction, acting against the plug 14, effects an inward movement of the rod 18, the adjusting nut 33, carried thereby, engages the outer end of the sleeve 28, and forces the sleeve to move in the same direction, thus bringing the edge of the washer 31, to bear on the fulcrums 26, on the lever 22, and thereby force the valve 23, to its seat, where it remains until the steam pressure shall fall and rise again. The lever 22, is mounted so as to drop by gravity when it is moved inwardly beyond its center of gravity. This provision operates to hold the valve on its seat when the steam pressure has fallen and the controller is cooled, the atmosphere, at this time, cooperating with the gravity of the lever to hold the valve seated, induced by the partial vacuum in the pipes caused by the receding steam vapor. When the controller cools, the expansion tube 10 contracts and moves the rod 18, back to normal position. The tension of the spring 32, may be adjusted to meet requirements of a positive pressure on the valve, and the sleeve may be adjusted to and from contact with the fulcrum knife bearings 26, by turning the nut 33, in the direction required.

Having fully described my invention, what I claim is:—

In a vapor-vacuum controller, the combination with the casing having an inlet and an outlet with a valve seat, of an expansion tube suspended in the casing and having its inner end closed and its opposite end open to atmosphere, a carrier mounted on the inner side of the closed end of the said tube and projected outwardly of the casing, a lever having pivotally mounted bowed arms surrounding said carrier, said arms being provided with oppositely disposed transverse fulcrum knife bearings, a valve having a stem movably engaged by the free end of said lever and adapted to close the outlet in the casing, a sleeve slidably mounted on the projecting portion of said carrier and

having an inwardly extending annular flange at its inner end, a cup-shaped washer mounted on the inner end of said sleeve, the peripheral edge of said washer being adapted to press on the fulcrum knife bearings on said lever, a coiled spring mounted on said sleeve and adapted to press on said washer,

means for adjusting the tension of said spring, and means for adjusting said sleeve to and from said lever.

FREDERICK P. HITCHCOCK.
